MOBILE MONITORING UNIT

Elmo T. Evans, La Crescenta, and Warren W. White,
Sierra Madre, Calif., assignors to Hycon Mfg. Com-
pany, Pasadena, Calif., a corporation of Delaware

Application July 1, 1957, Serial No. 46,782

Term of patent 14 years

(Cl. D14—3)

FIG. 1

Des. 184,279

PAGE 2

FIG. 2

FIG. 3

FIG. 4

Des. 184,279

PAGE 4

FIG. 5

FIG. 6

Figure 1 is a perspective view taken from the side and rear of a mobile monitoring unit, embodying our new design;

Figure 2 is a side elevational view;

Figure 3 is a rear elevational view;

Figure 4 is a front elevational view;

Figure 5 is a side elevational view, showing the side opposite that shown in Figure 2; and

Figure 6 is a top plan view thereof.

The essential features of our design reside in the portions shown in full lines.

We claim:

The ornamental design for a mobile monitoring unit, substantially as shown and described.
